SHOE SEWING MACHINE

Cyril Catly Sheffield and George Clarke, Leicester, England, assignors to United Shoe Machinery Corporation, Paterson, N. J., a corporation of New Jersey

Application January 5, 1934, Serial No. 705,404
In Great Britain January 7, 1933

4 Claims. (Cl. 112—60)

The present invention is concerned with improvements in or relating to the manufacture of footwear and sewing machines suitable for use therefor. The invention has particular reference to means for producing an article of footwear simulating in appearance, and having the qualities of, the so-called Sahara sandal while obviating the thonging together by a lace or thong, of the upper and sole which has ordinarily 5 characterized that sandal and which has usually been a tedious and slow hand operation and therefore costly and generally objectionable to footwear manufacturers. The invention is hereinafter illustratively described with reference to 10 the sewing together by means of a specially organized curved hooked needle lockstitch sewing machine of an upper having a bead around its margin and a sole having an upturned marginal portion having a flange turned outwardly there- 15 from, the stitching passing through said flange and through the upper adjacent to the bead which serves to conceal it in the finished shoe. As hereinafter illustratively described, the special organization of the machine may comprise 20 the provision of a presser foot which is suitably grooved to receive the bead on the upper and a work positioning member adapted to engage the work at the interior of the shoe. Conveniently also the presser foot has a substantial degree 25 of extension along the line of work feed and has a slot formed therein through which the needle operates. Further, the machine may be provided with suitable stopping and starting mechanism to enable the operator accurately to 30 control the sewing operation by sewing, according as he desires, either a succession of stitches or only a single stitch at a time. Yet again, it is convenient, as hereinafter explained to provide the machine with treadle or like means 35 upon actuation of which at the conclusion of a sewing operation the presser foot is raised from the work and only after the presser foot has started to rise, needle thread locking means of the machine, which means is in locking position 40 when sewing stops, is released.

The various objects of the invention and the several features thereof will become evident to those skilled in the art from the following description, given with reference to the accompanying drawings, of an illustrative organization of a curved hooked needle lockstitch sewing machine to enable it to perform the sewing together of an upper and a sole of the characters already indicated, while the said features are clearly set out in the appended claims.

In the accompanying drawings:

Figure 1 is a right hand side elevational view of the head portion of a curved hooked needle lockstitch sewing machine of the general nature of that disclosed in U. S. Letters Patent to French and Meyer No. 473,870 dated April 26, 1892, but equipped with novel parts to enable it to perform the sewing of an outwardly directed flange moulded on the periphery of the rim of a Sahara sandal type of sole to a beaded 10 upper;

Figure 2 is a right hand side elevational view of certain parts seen in Figure 1 drawn to a larger scale than Figure 1 and indicating a sole and upper in position for being sewn together;

Figure 3 is a front elevational view of certain of the sewing instrumentalities and work engaging parts of the machine;

Figure 4 is a perspective view of the work table of the machine;

Figure 5 is a perspective view of the presser foot of the machine;

Figure 6 is a detail sectional view of a work engaging roll of the machine;

Figure 7 is a perspective view of a type of 25 Sahara sandal for the sewing together of the sole and upper of which the machine shown in Figure 1 is well adapted, the shoe being shown as it appears immediately after the sewing operation; and

Figure 8 is a cross-sectional view of the shoe 30 shown in Figure 7, taken along the line VIII—VIII in Figure 7.

Referring first to Figures 7 and 8, a type of 35 Sahara sandal, with the sewing together of the upper and sole of which the present invention is particularly concerned, comprises a sole 1 having an upstanding rim 3, moulded all around it. The upper edge of the rim 3 is turned outwardly (all around the rim) to form a flange 40 5 which is substantially parallel to the marginal portion of the sole tread. Conveniently the sole is moulded to the form just mentioned in one operation by moulding between suitably shaped co-operating moulds. The upper of the sandal 45 is conveniently formed of two separate portions, a toe portion 7 and a heel portion 9. The portions 7 and 9 of the upper have each sewn to their lower edges (while the portions 7 and 9 are in the loose state) a bead 11 (best shown in Figure 8) which may consist of a thin leather strip folded around a reinforcing cord. As shown in Figure 8, the two end portions of the bead attached to the toe portion 7 of the upper project for some distance beyond the ends of the por- 50 55

tion 7 and when the shoe is assembled, the toe portion 7 and the heel portion 9 of the upper do not meet but the intervening space at each side of the shoe is bridged by the projecting end 5 portion of the bead last referred to, which end portions are sewn to the sole in the same way as the remainder of the bead. The points at 10 which these end portions of the bead on the toe portion 7 of the upper meet the ends of the bead on the heel portion 9 of the upper are shown at 13 in Figure 7. In sewing the sole and upper of the sandal together by a machine, as hereinafter described, the operator will, prior to beginning sewing say the heel portion 9 of the 15 upper to the sole, make marks on the upper surface of the flange 5 of the sole at the localities 13 to ensure that the heel portion 9 of the upper (which can readily be located to the marks) will be sewn in correct position to the sole. The 20 marks themselves can readily be made in correct position on the sole by employing a suitably designed template.

The curved hooked needle lockstitch sewing machine illustrated in Figures 1 to 6 is particularly adapted for the sewing together of the sole and upper of a sandal such as that just described. This machine, as regards its sewing instrumentalities, is (except as hereinafter described) of the general character of the machine 25 disclosed in the patent to French and Meyer above referred to, to which reference may be made for a full description of parts not herein specifically referred to. The machine comprises a curved hook-needle 15, a needle guide 17, an awl, 19, a looper 21, a take-up 23, a work table 25 and a presser foot 27. The machine is equipped with treadle actuated stopping and starting mechanism (not shown) of well known character so that the operator may either, according as he desires, sew a succession of stitches 30 or when proceeding more carefully sew only a single stitch at a time.

The work table 25 of the machine is of usual type except that as seen in Figure 4, the front wall 29 is preferably quite thin. This allows a seam to be sewn quite close to the apex of the angle between the flange 5 and the rim 3 when work is presented to the machine, as is indicated in Figure 2.

50 The presser foot 27 is shown particularly in Figure 5. Its work engaging portion has a substantial degree of extension along the line of feed and through this portion there is formed a slot 31 extending in the direction of feed and corresponding generally to the slot in the work table 25. The needle and awl operate through the slot 31 and the portion 33 of the presser foot between the forward wall of the slot and the front face of the presser foot acts during sewing 55 as a guard to shield the upper from damage by the needle or awl.

Along the under face of the presser foot with its axis to the rear of the longitudinal median line of the slot 31 there is formed a groove 35 of substantially semi-circular cross-section which extends in the direction of feed from end to end of the work engaging face of the presser foot. As is shown in Figure 2, this groove serves to engage the bead 11 on the upper to position the bead during sewing. The diameter of the groove 60 is preferably slightly in excess of that of the bead. The lower face of the portion 33 of the presser foot is well below the level of the highest part of the groove 35 so that the portion 33 of the presser foot enters well into the crease be-

tween the bead and the upper proper and holds the upper down towards the flange 5 on the sole at a little distance from the bead held by the groove. Thus a free passage is ensured for the needle and awl between the bead and upper (somewhat tensioned away from the bead by the portion 33 of the presser foot) so that the needle and awl can penetrate the upper reliably and uniformly at the crease last referred to. The opposite ends of the groove 35 in the presser foot 10 are conveniently rounded off somewhat so that there is a smoothed (and not a sharply angled) entry into and exit from the groove for the bead at the opposite ends of the presser foot.

To assist in supporting and positioning the work during sewing, the machine is provided with a horn arrangement clearly shown in Figure 1. This horn arrangement is of a similar general nature to the horn arrangement disclosed in U. S. Patent to Ricks and Reid No. 1,695,718 dated December 18, 1928. The horn arrangement is supported by two arms 37 (one of which is seen in Figure 1) secured by bolts 39 to the frame 41 of the machine. The top ends of the arms 37 support a horizontal shaft 43. A bracket 45 is 15 pivotally mounted on the shaft 43 and rigidly secured to a forward face of this bracket is a bearing member 47. A shaft 49, which is inclined at a small angle to the vertical (its upper end being slightly nearer to the back of the machine than its lower end) is journaled in the bearing member 47. At the lower end of the shaft 49 there is an enlarged portion 51 to which is clamped by bolts 53 a horn 55. The upper end of the shaft 49 is threaded and has upon it a nut 57. This 20 nut is adjusted so that although the shaft 49 can turn in the bearing member 47 it is not capable of moving axially with relation thereto. As is seen in Figure 1, the horn 55 is approximately C-shaped and carries at its lower end a work 25 positioning member in the form of a roll 59 which is adapted to engage the work at the interior of the shoe. This roll comprises (see Figure 6) a metal hub 61 rotatably mounted on a screw 63, the axis of which is in line with the axis of the shaft 49, in threaded relation with the lower end of the horn 55. On the hub 61 is carried a solid rubber 30 tyre 65 about one inch and a quarter in diameter and some three eighths of an inch thick. The head of the screw 63 is countersunk into the hub 61 so that a smooth flat lower face is presented by the roll towards the inner face of the sole during 35 sewing. The periphery of the rubber tyre 65 is suitably contoured to cooperate (as shown in Figure 2) with the inner face of the sole rim 3 in holding the outer face of the rim against the front face of the work table 25 as the sole is fed past the sewing point with its flange 5 resting on the upper surface of the work table 25. The 40 height of the roll 59 is such that its area of contact 45 with the inner surface of the rim 3 of the sole is about on the same level as the area of contact of the front face of the work table 25 with the outer surface of the rim. The bracket 45 has a rearwardly extending arm 67 on which is trunnioned a block 69 through which passes a rod 71 having, above the block, an adjusting nut 73 and a lock nut 75 threaded upon it, and below the block a compression spring 77 mounted upon it 50 and confined between the block and a collar 79. The rod 71 is pivotally connected at its lower end to a lever 80 which is oscillated from a cam on the cam shaft 81 of the machine. This causes 55 a swinging motion of the bracket 45 about the 60

70 block 69. The lever 80 is connected to a cam 75 on the cam shaft 81 of the machine. This causes a swinging motion of the bracket 45 about the 75

shaft 43 and so of the roll 59 about the same axis. The distance between the roll 59 and the shaft 43 is such that since the movement of the roll 43 is between its extreme positions is very small, being 5 conveniently about one sixteenth of an inch, this movement is practically in a straight line towards and away from the work. The timing of the cam just mentioned is such that while the roll is maintained in the work clamping position shown in 10 Figure 2 for the major portion of a stitch forming cycle of the machine it is moved forwardly away from the work table 25 while the awl 19 is feeding the work and so cannot exercise a retarding action on the feed.

15 It has already been mentioned that the machine is fitted with a starting and stopping mechanism which is such that the sewing instrumentalities on stopping always come to rest in the same positions, these being such that the needle 15 is withdrawn upwardly from the work, the awl 19 is withdrawn downwardly from the work, the presser foot 27 is in engagement with the work and the roll 59 is in its rearward work clamping position. Further at the stopping position 20 25 the needle thread lock, which is of well known form, is operative to prevent thread being withdrawn from the thread supply. In order that at the conclusion of a sewing operation the work may be readily withdrawn, the machine is provided with a treadle upon one continued depression of which the presser foot is first unlocked, then it is raised, then after the presser foot has risen slightly the thread lock is released and finally the roll 59 is withdrawn forwardly from 30 35 the sole enabling the work to be easily removed. This treadle is not itself shown in the drawings but it is connected to a treadle rod 83, depression of the treadle causing depression of the treadle rod which is normally spring pressed upwardly.

40 The arrangement whereby the presser foot is unlocked and then raised upon depression of the treadle rod 83 will now be described. The presser foot 27 is carried at the forward end portion of a bent lever 85 pivoted towards its middle upon 45 a stud 87 carried by the frame. The rear end portion of the lever 85 has secured to it a rack 89 and the teeth of this rack are adapted to be engaged by two-three-toothed pawls 91, 93 pivoted about the same axis on the machine frame. When 50 55 a tooth of the rack is engaged by one of the pawls, the presser foot 27 is locked against upward movement. The teeth of the pawl 93 are displaced from the teeth of the pawl 91 by a distance equal to about half the distance between successive teeth on the rack 89. This arrangement allows the presser foot 27 to be locked in twice the number of positions that it could be if only a single pawl were employed. The lever 85 has pivoted to it at 95 another lever 97. The lever 97 has a lug 60 65 70 75 77 79 81 83 85 87 89 91 93 95 97 99 101 103 105 107 109 111 113 115 117 119 123 125 127 129 131 133 135 137 139 141 143 145 147 149 151 153 155 157 159 161 163 165 contact with the boss 123 on the lever 85. Then if the hand lever is still pressed rearwardly the lever 85 will be turned in a clockwise direction about the stud 87 and the presser foot raised 5 from the work.

The presser foot actuating mechanism as so far described with relation to the parts 85, 89, 91, 93, 97, 111, 113, 117, 101, 109, 133, 139, etc., has previously been employed on sewing machines of the general nature of that disclosed in the patents to French and Meyer above referred to and in itself forms no part of the present invention. We have now arranged however that the presser foot is unlocked and raised on 15 depression of the treadle hereinbefore referred to. The treadle rod 83 has a collar 159 secured thereto by a set screw 161. The treadle rod 83 passes through a fork at the forward end of a lever 163 which is rigidly secured at its rear end 20 to a horizontal rock-shaft 165 carried by the two fixed arms 37 already referred to. The lever 163 has secured to it a portion 167 and a link 169 is pivoted at its rear end to the portion 167, a slot being provided whereby the position of the 25 pivot may be adjusted. The forward end of the link 169 is pivoted at 171 to a lug projecting from the elbow lever 139. The arrangement is such that on depression of the treadle rod 83 the collar 159 swings the lever 163 counter-clockwise 30 as seen in Figure 1. This in turn causes the link 169 to turn the elbow lever 139 in a clockwise direction and this is exactly the same way as hereinbefore described with reference to the movement of the hand lever 133 causes the 35 presser foot 27 to be first unlocked and then raised upwardly.

It has been mentioned hereinbefore that when at the end of a sewing operation the treadle rod 83 is depressed and after it has started to raise the presser foot 27 the needle thread lock of the machine (which will be in its locked position when the machine stops) is released. The general arrangement of the thread take-up 23 and thread lock is the same as in the machine of Patent No. 473,870. The thread coming from the looper 21 passes around a roll at the end of the take-up lever 23 then around a roll at the end of the auxiliary take-up lever 173 then around a roll 175 against which it may be 40 clamped at suitable times by the thread locking lever 177 and then around a roll on the pull-off lever 179 from which it passes round a tension device to the supply. The thread locking lever 177 is pivoted on a horizontal shaft 181 and its rearward end is engaged by a forked member 183 rigidly secured to a horizontal rock shaft 185. The rock-shaft 185 is actuated from a cam in 45 the same manner as is described with reference to corresponding parts in the specification of Letters Patent No. 473,870.

The rock-shaft 185 has a lever 191 loosely pivoted thereon. The upper end of the lever 191 is connected by a pivoted link 193 with an arm 195 rigidly secured to the rock shaft 185. The lever 191 when swung clockwise as seen in Figure 1 is 50 adapted to contact with the arm 187 and swing this arm and so the rock-shaft 185 clockwise as seen in Figure 1 which in turn will cause the thread locking lever 177 to be swung counter-clockwise about its pivot so that its thread clamping end is swung away from the roll 175. Thus it will be realized that when the treadle rod 83 is depressed and the rock-shaft 185 is rotated in a counterclockwise direction the arm 195 will 55 be moved to cause clockwise motion of the lever 70

191 and thus to cause release of the thread lock. The degree of motion permitted to the lever 191 before it contacts with the arm 187 is such that the thread lock will only be released after the treadle rod 83 has been depressed such a distance that the presser foot 27 has started to rise. 5

It has been mentioned hereinbefore that after the treadle rod 83 has unlocked and raised the presser foot and released the thread lock its final depression is operative to withdraw the roll 59 10 forwardly from the sole. For this purpose the treadle rod 83 has an eye 197 formed upon it at its top end which embraces a pin 199 projecting from a lever 201 which is loosely pivoted on the horizontal shaft 43 already referred to. The lever 201 has a lug 203 formed upon it which after the treadle rod has been depressed through some distance (to unlock the presser foot and release the thread lock) is adapted to contact with a lug 205 formed on the rearwardly extending arm 67 of the bracket 45. Further depression of the treadle rod then causes the bracket 45 to be swung clockwise, as seen in Figure 1, about the horizontal shaft 43 which results in the roll 59 being withdrawn forwardly from the 25 work.

There is a virtue in the order hereinbefore described in which the various actions take place upon depression of the treadle rod 83. If the machine is stopped (as many frequently occur) 30 before a shoe has been completely sewn the operator may desire to lift the presser foot slightly to position the work correctly should it have become displaced. It will be realized that by depressing the treadle rod through a short distance 35 only he can raise the presser foot somewhat without releasing the thread lock or moving the roll 59 forwardly both of which latter effects would be disadvantageous since release of the thread lock might result in a loosening of the stitches 40 and forward movement of the roll 59 from its sole clamping position might result in displacement of the sole if the operator were not to continue to hold it in position.

It is believed that the operation of the machine 45 described with reference to Figures 1 to 6 will have become clear from the foregoing. Briefly to recapitulate however the operator to sew such a shoe as is shown in Figures 7 and 8 will take the sole 1 and position thereon say the heel portion 9 of the beaded upper (the sole preferably having had, as hereinbefore mentioned, marks made thereon at the localities 13 at which the heel portion 9 of the upper should end). Then he will depress the treadle connected to the treadle rod 50 83 until the presser foot 27 is raised and the roll 59 moved forwardly and while the parts are in this position he will present the assembled work with the sole lowermost (at one end of the heel portion 9 of the upper) to the machine and release 55 the treadle just mentioned so that the presser foot 27 is lowered so that its groove 35 engages the bead 11 on the upper and the roll 59 is moved rearwardly so that the rim 3 of the sole 1 is clamped between it and the work table 25 as is 60 shown in Figure 2. Depression of the treadle which is connected to the stopping and starting mechanism will cause the machine to begin sewing a lockstitch seam (indicated at 207 in Figure 8) 65 to unite the sole and upper, the needle entering the upper before it enters the sole. As already mentioned hereinbefore the stopping and starting mechanism is such that a depression and immediate release of the treadle last referred to causes the machine to sew one stitch only but if this 70 75 80 85 90 95 98 99

treadle be retained depressed the machine will continue to sew a succession of stitches until the treadle is released. This arrangement allows the operator very satisfactorily to control the sewing operation. When the heel portion 9 of the upper has been sewn to the sole, the toe portion 7 will thereafter be sewn to the sole in corresponding fashion, the sewing being made to extend along the portions of the bead 11 attached to the toe portion 7 of the upper which project beyond the toe portion 7 proper up to the localities 13 at which the heel portion 9 of the upper begins.

It will, of course, be realized that no last is employed in the shoe during the sewing operation. Conveniently after the sewing operation has been completed, a last may be inserted in the shoe and the bead 11 on the upper subjected to a smoothing or beating operation whereby it is pressed up closely towards the upper to conceal the sewing 207 while the edge of the flange 5 of the sole may be trimmed more closely up to the sewing 207, preferably to a somewhat rounded form.

While the above description of the operation of the machine has been given with relation to the sewing of a sandal in which the upper is composed of two portions, it is, of course, to be realized that the machine may be readily used in a similar manner for the sewing of a beaded upper made in one unit to an outturned flange of a sole such as 1.

The nature and scope of the invention having been indicated, and a machine embodying the several features of the invention having been specifically described, what is claimed is:

1. A shoe sewing machine for sewing the lower edge of an upper to the out-turned flange formed on a rim upstanding from the tread portion of the sole having, in combination with the stitch forming devices, a work support shaped and arranged to support the outturned flange of the shoe sole, a presser foot cooperating with the work support to clamp the upper and flange intermittently, a horn extending into the shoe and pressing the rim of the shoe sole against the edge of the work support, and means for moving the horn away

from the work support during each stitch forming cycle to facilitate feeding of the work.

2. A shoe sewing machine for sewing the lower edge of an upper to the out-turned flange formed on a rim upstanding from the tread portion of the sole having, in combination with the stitch forming devices, a work support shaped and arranged to support the out-turned flange of the shoe sole, a presser foot cooperating with the work support to clamp the upper and flange intermittently, a horn extending into the shoe provided at its inner end with a roll arranged to press the rim of the sole against the edge of the work support, and means for supporting the horn so as to be capable of a movement of rotation about an axis coincident with the axis of the roll.

3. A shoe sewing machine for sewing the lower edge of an upper to the out-turned flange formed on a rim upstanding from the tread portion of the sole having, in combination with the stitch forming devices, a work support shaped and arranged to support the outturned flange of the shoe sole, a presser foot cooperating with the work support to clamp the upper and flange intermittently, a horn extending into the shoe and pressing the rim of the shoe sole against the edge of the work support, and means operable upon stopping the machine to lift the presser foot and move the horn away from the work support.

4. A shoe sewing machine for sewing the lower edge of an upper to the out-turned flange formed on a rim upstanding from the tread portion of the sole having, in combination with the stitch forming devices, a work support shaped and arranged to support the out-turned flange of the shoe sole, a presser foot cooperating with the work support to clamp the upper and flange intermittently, a horn extending into the shoe and pressing the rim of the shoe sole against the edge of the work support, and a treadle and suitable connections acting when actuated to lift the presser foot from the work and thereafter continue the lifting movement of the presser foot and move the horn away from the work support.
